UNITED STATES PATENT OFFICE

NELSON M. BAKER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS

DESIGN FOR AN END PIECE FOR AN OPHTHALMIC MOUNTING

Application filed April 5, 1930. Serial No. 35,176. Term of patent 14 years.

To all whom it may concern:

Be it known that I, NELSON M. BAKER, a citizen of the United States, residing at Southbridge, in the county of Worcester and State of Massachusetts, have invented a new, original, and ornamental Design for an End Piece for an Ophthalmic Mounting, of which the following is a specification, reference being made to the accompanying drawings forming part thereof.

Fig. 1 is a perspective view of an endpiece for an ophthalmic mounting, showing my new design of endpiece in full lines and fragments of the lens rim and temple in dotted lines to show the relation of the design when in use.

Fig. 2 shows a similar view of the endpiece shown in Fig. 1, but on a highly enlarged scale.

The contours of the endpiece are shaped into cubist facets which, due to their selected angular relations and highly polished surfaces, produce a pleasing effect similar to that of facets cut on a precious gem, when light impinges thereon. This effect is adapted to change when the endpiece is viewed from different angles and is intended to be conservative and to the taste of most individuals.

I claim:

The ornamental design for an endpiece for an ophthalmic mounting as shown and described.

In testimony whereof, I affix my signature.

NELSON M. BAKER.
